UNITED STATES PATENT OFFICE.

JOHN TREACY, OF ST. PAUL, MINNESOTA.

DETACHABLE POINT FOR POWER-SHOVEL TEETH.

No. 802,178.

Specification of Letters Patent.

Patented Oct. 17, 1905.

Application filed May 9, 1905. Serial No. 269,606.

To all whom it may concern:

Be it known that I, JOHN TREACY, of St. Paul, Ramsey county, Minnesota, have invented certain new and useful Improvements in Detachable Points for Power-Shovel Teeth, of which the following is a specification.

The object of my invention is to provide a power shovel or scoop tooth point which can be easily and quickly removed from the tooth for sharpening purposes or in case of breakage.

A further object is to provide a tooth-point that will not work loose even when subjected to a severe strain.

The invention consists generally in various constructions and combinations, all as herein-after described, and particularly pointed out in the claims.

In the accompanying drawings, forming part of this specification, Figure 1 is a plan view of a power-shovel tooth with my improved point applied thereto. Fig. 2 is a longitudinal section through the end of the tooth and point. Fig. 3 is a transverse section on the line *xx* of Fig. 1. Fig. 4 is a transverse section on the line *yy* of Fig. 2, and Fig. 5 is a side view showing the point detached from the tooth.

In the drawings, 2 represents the upper shank of the tooth, and 3 the lower one, between which is a slot 4 to receive the cutting edge of the power-shovel bucket or scoop. (Not shown.) Holes 5 are provided in said shank, through which rivets pass to secure the tooth on the bucket. The forward end of the tooth projects beyond the cutting edge of the bucket and is provided with a vertical socket 6, gradually decreasing in area from the top toward the bottom of the tooth.

7 represents the tooth-point, having preferably an under face which forms a continuation of the shank 3 and a beveled upper face tapering to a point. A web 8 is provided on one end of said point, having at its end a tongue 9, which is substantially circular in cross-section and tapered from the top toward the bottom of the point and adapted to enter the socket 6 and fit snugly therein, and pressure on the beveled upper surface of the point will serve to wedge it more firmly in the tooth-socket. To prevent accidental separation of the point from the tooth, I provide a hole 10 in the web 8, adapted to coincide with similar holes 11 in the tooth, and these holes preferably decrease in area from one side of the tooth to the other and are adapted to receive a tapered pin 12, the ends of which prefer-

ably project beyond the sides of the tooth for convenience in removing the pin or tightening it. Whenever desired this point can be easily and quickly detached from the tooth and sharpened or a new point substituted therefor. When the point is put in place on the tooth, it will be held firmly between the tapered walls of the vertical socket and the long bearing-surfaces of the tooth on the point upon each side of the web, and vertical oscillation of the point will be prevented, and at the same time the end of the tooth will brace and support the point when the shovel is in use.

I claim as my invention—

1. A shovel-tooth having a socket in its end tapering from one end to the other, and a detachable point having a web on one end and a tapered tongue fitting within said socket, substantially as described. 75

2. A shovel-tooth having a vertical socket in its end tapered from the top toward the bottom of the tooth, and a detachable point having a vertical web on one end that terminates in a tongue tapered from its upper toward its lower end and adapted to enter said socket and fit snugly therein, substantially as described. 80

3. A shovel-tooth having a socket in its end in combination with a detachable point having a web on one end and a tongue to enter said socket, the end of said tooth having a broad bearing-surface on said point upon each side of said web whereby said point is braced and strengthened, substantially as described. 90

4. A shovel-tooth having a vertical socket in its end tapered from the top toward the bottom in combination with a detachable point having a web on one end and a tongue tapered from the top toward the bottom and adapted to enter said socket and fit snugly therein, and the end of said tooth having a broad vertical bearing-surface on said point upon each side of said web, and a removable pin passing through said tooth and web, for the purpose specified. 95

5. A shovel-tooth having a vertical socket in its end tapering from the top toward the bottom, and a detachable point having a tapered tongue to fit within said socket, substantially as described. 105

In witness whereof I have hereunto set my hand this 3d day of May, 1905.

JOHN TREACY.
